UNITED STATES PATENT OFFICE.

BERT C. BROWN, OF AVOCA, NEW YORK.

DESIGN FOR A GAME-BOARD.

SPECIFICATION forming part of Design No. 34,594, dated May 28, 1901.

Application filed May 1, 1901. Serial No. 58,402. Term of patent 3½ years.

To all whom it may concern:

Be it known that I, BERT C. BROWN, a citizen of the United States, residing at Avoca, in the county of Steuben and State of New York, have invented and produced a new and original Design for Game-Boards; and I do hereby declare the following to be a full, clear, and exact description of the same, reference being had to the accompanying drawings, forming a part thereof.

Figure 1 of the drawings is a plan view of a game-board, illustrating my design; Fig. 2, a transverse sectional elevation of the game-board.

The distinctive feature of my design for game-boards resides in a circular base A, having upon its upper surface two circular rings near the periphery or outer edge and near the center of the board, respectively, said rings being formed by the double lines *a b* and the double lines *c d*, the lines being concentric with the axial center of the base, and also the radiating lines arranged in pairs, as indicated at *e f*, which lines extend from the center to

the outer edge of the board, and the radiating lines *g h*, extending from the circular line *c* to the outer edge of the board and between each pair of lines *e f*, also the lines *i j*, extending radially from the circular line *a* to the outer edge of the board. The lines *e f* are shown as crossing the circular lines *a b* and *c d* and the lines *g h* as crossing the circular lines *a b*. Each pair of lines *e f* and *g h* have cross-lines *k l*, and the circular lines *c d* have cross-lines *m n*, a broken circular line *o* being formed at the center of the board.

Having fully described my design, what I claim, and desire to secure by Letters Patent, is—

The design for game-board, substantially as herein shown and described.

In testimony whereof I affix my signature in presence of two witnesses.

BERT C. BROWN.
